UNITED STATES PATENT OFFICE.

CLARENCE WARNER, OF DAYTON, OHIO, ASSIGNOR TO DELCO-LIGHT COMPANY, OF DAYTON, OHIO, A CORPORATION OF DELAWARE.

PUMPING APPARATUS.

Application filed October 23, 1923. Serial No. 670,356.

To all whom it may concern:

Be it known that I, CLARENCE WARNER, a citizen of the United States of America, residing at Dayton, county of Montgomery, State of Ohio, have invented certain new and useful Improvements in Pumping Apparatus, of which the following is a full, clear, and exact description.

This invention relates to pumping apparatus of the suction type, and has for its object the provision of a simple and compact pumping unit, tending toward a reduction in the number of parts.

Further objects and advantages of the present invention will be apparent from the following description, reference being had to the accompanying drawing, wherein a preferred embodiment of one form of the present invention is clearly shown.

20 In the drawings:

Fig. 1 is a view partly in elevation and partly in section of a pumping apparatus comprising the present invention.

25 Fig. 2 is a sectional view on a reduced scale taken on the line 2—2 of Fig. 1.

In the drawings, a power head frame 20 supports an electric motor 21 and encloses power driven mechanism which may be of the type disclosed in the copending application of G. A. Buvinger and C. Warner, Serial No. 626,174, filed March 19, 1923 (DL 147). An aperture 22 is provided in end wall 23 of frame 20. A cross head guide 24, supported within frame 20 receives a cross head 25 which is attached to a connecting rod 26 by a pin 27, the rod 26 being connected with the power driven mechanism referred to, whereby the cross head 25 is reciprocated within the cross head guide 24. 40 Cross head 25 is provided with a threaded extension 28.

A pump frame 30 is provided with an extension 31 being threaded adjacent the end thereof, and of such size as to be received by the opening 22 in wall 23 of frame 20. Extension 31 receives a nut 32 which when drawn up on extension 31 tightens the joint between wall 23 of frame 20 and wall 33 of pump frame 30. Frame 30 is provided with an inlet chamber 35 having a baffle 36 for keeping the pump valves under water to prevent drying out, and also for keeping the pump primed, and an outlet chamber 37 having a baffle 38 for maintaining a column of water in the pump and also keeping the valves

under water. Removable plugs 39 and 40 are provided in frame 30 for priming of the outlet and inlet chambers 37 and 35 respectively when the pump is first installed. Wall 41 of inlet chamber 35 is provided with an opening 42 for receiving a removable plug 43 for a purpose to be described, and chamber 35 is adapted to be drained through means of a plug 43. Pipe 45 connects inlet chamber 35 with a suitable source of supply, and pipe 46 connects the outlet chamber 37 with suitable service pipes. Outlet chamber 37 is adapted to be drained through means of a removable plug 46. Inlet and outlet chambers 35 and 37 respectively are connected by a cylindrical aperture 50 in alignment with aperture 42 in wall 41 between walls 51 and 52^a of pump frame 30, and a cylinder 52 is press-fitted between these two walls, and is internally threaded adjacent the end thereof nearest the inlet chamber 35, for receiving a removable valve seat 53 having ports 54 and 55 which connect the cylinder 52 with the inlet chamber 35. A screw 56 is mounted in valve seat 53 and provides a support for a spring 57 which bears against disc valve 58 slidably mounted on said screw, for normally resiliently maintaining valve 58 on its seat 53, thereby controlling ports 54 and 55.

Wall 33 and extension 31 of pump frame 30 are provided with an aperture 60 in alignment with apertures 42 and 50. Aperture 60 permits reciprocation therethrough of a connecting rod or plunger 65, one end of which has connection with the threaded portion 28 of cross head 25, the other end extending into cylinder 52 and having threaded connection with a piston 74, comprising a valve cage 66 and a plug 75 having threaded connection with the valve cage 66. Connecting rod 65 is of such size as to displace substantially one half of the volume of water which the cylinder 52 is capable of holding during the operation of the pump. Plug 75 is provided with an opening 67 connecting cylinder 52 with the interior of cage 66, and cage 66 is provided with outlet ports 68 and 69 leading into the interior of cylinder 52. An annular groove 77^a in plug 75 receives packing 78 which is held in place between plug 75 and valve cage 66 when plug 75 is screwed into cage 66. Plug 75 provides a piston head and also a seat 75^a for a valve 72 to be described. A

- screw 70, is provided with a reduced portion 76 which slidably fits within a bore 71^a in inwardly extending boss 71 which is formed integrally with the valve cage 66, 5 the head of screw 70 extending into the opening 67 in plug 75. A disc valve 72 is mounted on the threaded portion 77 of screw 70 and is securely held thereon between a washer 72^a which engages the head of screw 10 70 and a washer 72^b having threaded connection with portion 77 of screw 70. A spring 79 which surrounds boss 71, bears against washer 72^b and the wall 80 of valve cage 66 to normally resiliently maintain the valve 72 15 on its seat 75^a.

Aperture 60 is recessed providing a seat 85 for packing 86 which is spaced from packing 87 by a packing gland 88. A packing nut 89 has threaded connection with the 20 inner wall surface of extension 31 and when tightened up tends to hold packing 86, packing gland 88 and packing 87 in position for sealing the aperture 60 through which the connecting rod or plunger 65 is adapted to 25 be reciprocated. Rod 65 is provided with wrench holes 90 and 91 for a purpose to be described.

Mode of operation.

- 30 When the rod 65 is moved to the right thereby moving piston 74 to the right, as viewed in Fig. 1, by the pump driving mechanism referred to, a vacuum will be created in the cylinder 52 whereby the valve 35 58 will be opened and water will be drawn from the source of supply through pipe 45, inlet chamber 35 up over baffle 36, through ports 54 and 55 into the interior of cylinder 52. Then when the piston 74 is moved to 40 the left, as viewed in Fig. 1, the valve 58 will be closed and valve 72 will be opened, thereby permitting water to flow from the interior of cylinder 52, through inlet opening 67 and through outlet openings 68 and 45 69 into the outlet chamber 37, up over baffle plate 38 and down into outlet pipe 46 to the service pipes. However, inasmuch as the rod or plunger 65 is of such size as to displace substantially one half of the water 50 which the cylinder 52 is capable of holding during operation of the pump, about one half of the water in cylinder 52 will be discharged into the outlet chamber on the stroke of the piston 74 to the left, as viewed 55 in Fig. 1. Then upon the return stroke of piston 74 to the right, the water remaining in cylinder 52 will be forced into the outlet chamber, up over the baffle 38 and down into outlet pipe 46. Thus there is a 60 discharge of water for each stroke of the piston 74 in either direction, thus constituting the pump a double acting discharge pump. It should be noted, however, that the pump has a single acting intake as described. This result is accomplished by a 65

single set of valves, one a stationary valve carried by the cylinder 52 and the other a movable valve carried by the piston 74.

The pumping apparatus may be readily disassembled for repairs or replacement of parts. The packing nut 89 is first loosened from the extension 31, then the nut 32 is loosened and slipped back on the rod 65. Then the inlet pipe 45 and outlet pipe 46 should be disconnected from the pump frame 30, and a wrench engaged in the holes 90 and 91 in rod 65 to thereby loosen the rod 65 from the threaded portion 28 of cross head 25. The pump frame 30 with the rod 65, piston 74, cylinder 52 and valves 58 and 72 may then be removed in assembled relation from the power head frame 20, the extension 31 and rod 65 being withdrawn through opening 22 in wall 23 of frame 20. 70 75 80

The rod 65 may be removed through opening 42 in the pump frame 30 by removing plug 43 and loosening valve seat 53 from the cylinder 52. Removal of valve seats 53 brings valve 58 with it in assembled relation. Piston 74 including head 75, valve cage 66 and valve 72 may be removed as a unit from the rod 65. Piston head 75 may then be removed from valve cage 66, and valve 72, including spring 79, screw 70 and washers 72^a and 72^b may be lifted from valve cage 66 in assembled relation. 85 90 95

Opening 42 in wall 41 of frame 30 is of sufficient size to permit insertion or withdrawal of the cylinder 52.

While the form of embodiment of the 100 present invention as herein disclosed, constitutes a preferred form, it is to be understood that other forms might be adopted, all coming within the scope of the claims which follow. 105

What is claimed is as follows:

1. A pump of the class described comprising a hollow pump frame or casing having a tubular extension at one end whereby the same may be attached to a power head, an opening at its other end located in line with said extension, and internal walls whereby an inlet and an outlet chamber are provided within said casing; said casing having an internal cylinder receiving opening in line with said first mentioned opening and with said tubular extension; a pump cylinder held in place within said second mentioned opening and the ends of which open into said inlet and outlet chambers; a valved piston operating in said cylinder; a connecting rod extending from said piston through said tubular extension and whereby reciprocatory movement may be imparted to said piston; an inlet pipe leading into said inlet chamber; and an outlet pipe leading from said outlet chamber. 110 115 120 125

2. A pump of the class described comprising a hollow pump frame or casing 130

- having a tubular extension at one end whereby the same may be attached to a power head, an opening at its other end located in line with said extension, and internal walls whereby an inlet and an outlet chamber are provided within said casing; said casing having an internal cylinder receiving opening in line with said first mentioned opening and with said tubular extension of less diameter than that of said first mentioned opening; a pump cylinder held in place within said second mentioned opening and the ends of which open into said inlet and outlet chambers, and which cylinder is removable through said first mentioned opening; a valved piston operating in said cylinder; a plunger extending from said piston through said tubular extension and whereby reciprocatory movement may be imparted to said piston; an inlet passage in said casing leading from a low point therein upward and into said inlet chamber above the level of said cylinder; a valve carried by said cylinder; and an outlet pipe leading from said outlet chamber from a point below the upper end thereof. 55
5. A pump of the class described comprising a hollow pump frame or casing having a tubular extension at one end whereby the same may be attached to a power head, a cylinder located at a low level within said casing and in line with said extension, and internal walls whereby an inlet and an outlet chamber are provided within said casing, and which chambers extend above the upper limits of said cylinder and communicate one with one and the other end thereof; a valved piston operating in said cylinder; a connecting rod extending from said piston through said tubular extension and whereby reciprocatory movement may be imparted to said piston; an inlet pipe leading into said inlet chamber; an inlet valve carried by said cylinder; and an outlet pipe leading from said outlet chamber. 60
10. 3. A pump of the class described comprising a hollow pump frame or casing having a tubular extension at one end whereby the same may be attached to a power head, a cylinder located at a low level within said casing and in line with said extension, and internal walls whereby an inlet and an outlet chamber are provided within said casing, and which chambers extend above the upper limits of said cylinder and communicate one with one and the other end thereof; a valved piston operating in said cylinder; a connecting rod extending from said piston through said tubular extension and whereby reciprocatory movement may be imparted to said piston; an inlet pipe through which liquid is supplied to said inlet chamber; an inlet valve carried by said cylinder; an outlet pipe leading from said outlet chamber; and baffles, one in said inlet and another in said outlet chamber, whereby liquid operated upon is caused to flow first upward and then downward in each of said chambers. 65
15. 4. A pump of the class described comprising a hollow pump frame or casing having a tubular extension at one end whereby the same may be attached to a power head, a cylinder located at a low level within said casing and in line with said extension, and internal walls whereby an inlet and an outlet chamber are provided within said casing, and which chambers extend above the upper limits of said cylinder and communicate one with one and the other end thereof; a valved piston operating in said cylinder; a connecting rod extending from said piston through said tubular extension and whereby reciprocatory movement may be imparted to said piston; an inlet pipe leading into said inlet chamber; an inlet valve carried by said cylinder; and an outlet pipe leading from said outlet chamber. 70
20. 5. Pumping apparatus comprising, in combination, a power head frame, a pump frame removably secured thereto and including inlet and outlet chambers, a pump cylinder, a stationary valve supported by said cylinder for controlling communication between the inlet chamber and cylinder, a piston adapted to be reciprocated within said cylinder, a plunger extending from said power head frame into the pump frame and connected with said piston, a valve carried by said piston for controlling communication between the cylinder and outlet chamber, and means within said chambers for keeping the valves submerged. 75
25. In testimony whereof I hereto affix my signature. 80
30. CLARENCE WARNER. 85
35. 6. Pumping apparatus comprising, in combination, a power head frame, a pump frame removably secured thereto and including inlet and outlet chambers, a pump cylinder, a stationary valve supported by said cylinder for controlling communication between the inlet chamber and cylinder, a piston adapted to be reciprocated within said cylinder, a plunger extending from said power head frame into the pump frame and connected with said piston, a valve carried by said piston for controlling communication between the cylinder and outlet chamber, and means within said chambers for keeping the valves submerged. 90
40. 7. Pumping apparatus comprising, in combination, a power head frame, a pump frame removably secured thereto and including inlet and outlet chambers, a pump cylinder, a stationary valve supported by said cylinder for controlling communication between the inlet chamber and cylinder, a piston adapted to be reciprocated within said cylinder, a plunger extending from said power head frame into the pump frame and connected with said piston, a valve carried by said piston for controlling communication between the cylinder and outlet chamber, and means within said chambers for keeping the valves submerged. 95
45. 8. Pumping apparatus comprising, in combination, a power head frame, a pump frame removably secured thereto and including inlet and outlet chambers, a pump cylinder, a stationary valve supported by said cylinder for controlling communication between the inlet chamber and cylinder, a piston adapted to be reciprocated within said cylinder, a plunger extending from said power head frame into the pump frame and connected with said piston, a valve carried by said piston for controlling communication between the cylinder and outlet chamber, and means within said chambers for keeping the valves submerged. 100
50. 9. Pumping apparatus comprising, in combination, a power head frame, a pump frame removably secured thereto and including inlet and outlet chambers, a pump cylinder, a stationary valve supported by said cylinder for controlling communication between the inlet chamber and cylinder, a piston adapted to be reciprocated within said cylinder, a plunger extending from said power head frame into the pump frame and connected with said piston, a valve carried by said piston for controlling communication between the cylinder and outlet chamber, and means within said chambers for keeping the valves submerged. 105
